[57] CLAIM

The ornamental design for a temperature housing and baseplate, as shown and described.

DESCRIPTION

FIG. 1 is a perspective view of a thermostat housing from below and to its right.

FIG. 2 is a front elevation view of the thermostat housing in FIG. 1.

FIG. 3 is a right side elevation view of the thermostat housing in FIG. 1.

FIG. 4 is a left side elevation view of the thermostat housing in FIG. 1.

FIG. 5 is a bottom plan view of the thermostat housing in FIG. 1.

FIG. 6 is a top plan view of the thermostat housing in FIG. 1.

FIG. 7 is a bottom plan view of a baseplate forming a part of the thermostat housing shown in FIGS. 1-6.

FIG. 8 is a left side elevation view of a baseplate forming a part of the thermostat housing shown in FIGS. 1-6.

FIG. 9 is a right side elevation view of a baseplate forming a part of the thermostat housing shown in FIGS. 1-6.

FIG. 10 is a top plan view of a baseplate forming a part of the thermostat housing shown in FIGS. 1-6.

FIG. 11 is a front elevation view of baseplate forming a part of the thermostat housing shown in FIGS. 1-6.

FIG. 12 is a perspective view of the baseplate shown in FIGS. 7-11 from below and to its right.

FIG. 13 is a front projective view of a thermostat baseplate similar to that of FIGS. 7-12 but omitting lettering thereon; and,

FIG. 14 is a perspective view, from below and to its right, of the thermostat baseplate shown in FIG. 13.
